UNITED STATES PATENT OFFICE

147,319

DESIGN FOR A PERMANENT WAVE
MACHINE

Howard D. Chapman, Tulsa, Okla.

Application August 26, 1946, Serial No. 132,868

Term of patent 14 years

(Cl. D86—10)

To all whom it may concern:

Be it known that I, Howard D. Chapman, a citizen of the United States of America, residing at Tulsa, in the county of Tulsa and State of Oklahoma, have invented a new, original, and ornamental Design for Permanent Wave Machines, of which the following is a specification, reference being had to the accompanying drawing, forming part thereof.

Figure 1 is a front elevational view of a permanent wave machine showing my new design.

Figure 2 is a rear elevational view thereof.

Figure 3 is a top plan view thereof.

I claim:

The ornamental design for a permanent wave machine, substantially as shown.

HOWARD D. CHAPMAN.
